UNITED STATES PATENT OFFICE.

DORSEY EUGENE MOORE, OF BRUCETON, TENNESSEE, ASSIGNOR OF ONE-HALF TO
OLIVER A. HARKER, JR., OF PURYEAR, TENNESSEE.

FIRE-BOX ARCH.

Application filed October 9, 1926. Serial No. 140,491.

This invention relates to the arches used in the fire boxes of locomotive and stationary engines. These arches, as usually constructed, are of solid brick extending upward and forward from the tube sheet and acting to deflect the fire and the gases and products of combustion upward and forward and then through the fire tubes. These arches also are often constructed of hollow brick, constituting air tubes or flues which open upon the exterior of the fire box and conduct air to the fire. This lowers the temperature of the fire box by admitting cold air thereto and also requires that holes be drilled in the fire box for the passage of air. Furthermore, with this construction, when the arch begins to burn out from long wear, this cold air coming in through these openings cools down the fire box and in many cases causes the engine to fail in making steam. It is often the case also that the arch falls down into the fire box soon after it is installed, due to many differing causes and this lets the cool air in.

The general object of the present invention is to provide an arch formed of hollow bricks set end to end so as to constitute flues, these flues opening at the rear end of the fire box so as to receive flames and hot gases therefrom. These flames and hot gases pass out at the top or back end of the arch, causing a blast of flame which burns the gases that are passing over the back end of the arch, thus eliminating smoke as well as saving fuel. Furthermore, all the fine coal that falls on top of the arch is burned for the reason that the arch is much hotter on top than the solid arch now in use in all locomotives or the arch having cool air flues.

My invention is illustrated in the accompanying drawings wherein:—

Figure 1 is a vertical sectional view through a locomotive fire box showing my improved arch construction;

Fig. 2 is a transverse sectional view through the arch;

Fig. 3 is a fragmentary top plan view of the arch.

Referring to these drawings it will be seen that I have illustrated diagrammatically the fire box 10 of a locomotive engine, though my invention is not limited to use with locomotive engines. The fire box at

its rear end is defined by the tube sheet 11 and the bottom of the fire box is formed by the grate 12. Tubes 13 extend from the tube sheet. A water space 14 forms the rear wall of the fire box. My improved arch extends transversely across the fire box in the usual manner and is composed of a plurality of fire brick designated 15, each of these fire brick being formed with a longitudinally extending passage 16. There are as many rows of fire brick as is necessary to extend transversely across the fire box and the fire brick may be made either relatively narrow or relatively wide, as may be desired. The innermost fire brick 17 of each row has its end 18 cut off so as to fit snugly against the tube sheet 11 and has its under face cut away at the rear end of the fire brick as at 19, so as to provide an inlet opening for the flames and gases 75 arising from the coal bed. These flames and hot gases of combustion pass upward through the flues 16 and out through the upper ends of these flues and then pass forward through the fire tubes 13.

While I do not wish to be limited to any particular means for supporting the fire brick 15, I have illustrated the fire brick as being supported by two 6½" siphon tubes 20 and two 3" circulation tubes 21 which extend from the water space of the boiler to the water space 14. Each brick under these circumstances is cut away at its lower corners, as at 22, to fit over these tubes 20 and 21, and thus the bricks cannot shift out of place.

As before remarked, I do not wish to be limited to the use of relatively small brick in locomotive boilers but relatively larger arch brick may be used on stationary boilers. 95 These bricks will be longer than the bricks illustrated in the drawing and need not be supported by means of siphon tubes or the circulating tubes but the arch will extend downward and laterally from a keystone 100 brick and thus will be self-supporting. Obviously, the detailed construction of the brick may be varied in many respects without departing from the spirit of the invention.

This construction causes the gases from the top of the fire to be burned by passing them through the hollow flues in the arch bricks so that the carbon is burned with the gases before the gases leave the fire box. 110

My construction does not require any changes to be made in order to install it in the fire box. No matter what happens to the arch no cold air can be let in and with my construction should the arch be defective in any manner, the fuel would burn in the same manner as if no arch was used, whereas with arches having cold air ducts passing through them any defect in the arch causes the cold air to be discharged into the fire and reduces the temperature to such an extent that the engine will not make steam. All the fine coal which is liable to fall upon the top of the arch will burn with my construction due to the arch being particularly hot. This prevents the unburned coal from stopping up the bottom rows of flues, causing leakage and engine failures. Furthermore, this arch collects no "honey comb" because the arch is too hot for the "honey comb" to stick to it. The arch further acts as a mixing and combustion chamber and by burning more of the gases causes a higher fire box temperature which in turn causes a higher degree of superheat. Furthermore this arch secures

an even temperature all over the bricks by having heat inside as well as out.

I claim:—

In a furnace fire box, an upwardly and forwardly extending arch formed of a plurality of longitudinally extending courses of brick, the bricks of each course being hollow and communicating with each other to thereby form flues straight from end to end and discharging at their upper ends at the crest of the arch, said arch terminating short of the rear wall of the fire box, the lower end of each flue opening upon the underface of the arch at the forward end thereof, the bricks of each course being cut away at their lower corners, and tubes extending upwardly and longitudinally through the fire box and engaging the cut away corners of the bricks to support the arch, said tubes communicating with the water space of the boiler.

In testimony whereof I hereunto affix my signature.

DORSEY EUGENE MOORE.
